UNITED STATES PATENT OFFICE

CESARE CIPPITELLI, OF FRANKFORT-ON-THE-MAIN, GERMANY, ASSIGNOR TO FIRM
VOIGT & HAEFFNER A. G., OF FRANKFORT-ON-THE-MAIN, GERMANY

CONTACT DEVICE

Application filed January 6, 1931, Serial No. 507,032, and in Germany January 21, 1930.

This invention relates to an electrical contact device consisting of a contact pin and a contact sleeve which is formed of contact fingers or stampings bent at an angle and arranged concentrically about the contact pin, one behind another. According to the invention the contact fingers or stampings of the contact sleeve have at the middle part a web-like extension with a large and a small curved out part and are arranged one after another, the curved part of one contact finger or metal stamping having the smaller diameter being inserted in the curved part having the larger diameter of the next contact finger.

Some constructional examples of the invention are illustrated in the accompanying drawings.

In Fig. 1 a single contact finger or metal stamping is illustrated in side elevation.

Fig. 2 is an end elevation of Fig. 1,

Fig. 3 shows schematically the assembly of a part of the metal stampings forming the contact sleeve in a plan view.

Figs. 4 and 5 are two elevations at right angles partly in section of a contact device which is intended especially for use at the end contact of a sliding disconnecting switch.

Figs. 6 and 7 show two elevations at right angles partly in section of a contact device which is intended for a contact pin passing through it.

Fig. 8 is an elevation of a contact device which can be used as a sliding disconnecting switch for open air plants.

In Fig. 9 the same device is shown in the off position.

Fig. 10 shows a part of a contact finger or metal stamping on a large scale.

According to Figs. 1-3 the angularly bent contact fingers or stampings 1, which form the contact sleeve are provided at their middle parts with web-like extensions which have larger curved out parts 1a and smaller curved out parts 1b. The V-shaped resilient contact fingers and their web-like extension with recesses are formed from single pieces of sheet metal. The smaller recess 1b of each contact finger 1 is inserted in the larger

recess 1a of the next contact finger. The present device is distinguished from other contact devices which have contact sleeves formed by angularly bent or V-shaped contact fingers by the fact that it enables a simple putting together or assembly of the separate contact fingers. Tongues 1c are provided at each end of the larger recess 1a of the contact finger 1. The tongues 1c are bent sideways as shown in Figure 3 after the contact fingers or metal stampings have been put together and consequently prevent the contact fingers being displaced in the direction of the longitudinal axis of the contact pin. The same effect could also be obtained by other bent tongues. The contact sleeve is preferably placed in a second protective sleeve or housing which is indicated in Fig. 3, by the arc 4. In this figure the contact pin is not shown. The contact is made with the free ends of the V-shaped contact fingers, i. e. the ends opposite the protective sleeve or housing 2.

The contact sleeves which are used in the constructional examples according to Figs. 4-9, correspond to those of Figs. 1-5 and in the first mentioned figures are only shown diagrammatically on account of the great simplicity.

According to Figs. 4 and 5, the contact sleeve formed of the V-shaped contact fingers 1 is set in a cup-like metal housing 4 pressed out of one piece. One side of the metal housing 4 is bent over to form a securing flange 4a and a tongue 4c is pressed out of its bottom 4b, so that on the one hand a second securing flange and on the other an opening 5 for introducing the contact pin, are formed. The protective metal housing 4 is secured to the angle piece 6 which is carried by the supporting insulator 7, by means of its two flanges, 4a and 4c, by screwing.

According to Figs. 6 and 7 the contact sleeve formed of the contact fingers is placed in a housing 4, which by means of flanges 4a, 4c, is secured to an angle piece 6 which is provided on a supporting insulator 7. The housing 4 has at its two ends openings 5a, 5b, which are closed by guiding discs 8

of rectangular cross section for the contact pin 9. In the constructional examples according to Figs. 4-7 the provision of laterally bent tongues is unnecessary because the displacement of the contact pieces in the direction of the longitudinal axis of the contact pin is prevented by the construction of the housing encircling the contact sleeve.

The contact device according to Figs. 8 and 9 consists of two contact sleeves 10a, 10b, formed of V-shaped contact fingers. The contact sleeve 10a is mounted in a stationary cup-like protective sleeve or housing 11a, which has a tubular extension 12 closed at the top. The second contact sleeve 10b is mounted in a movable cup-like protecting sleeve or housing 11b, the upper part of which carries the contact pin 13, which is guided in the contact sleeve 10a. The contact sleeve 10b and the protective contact sleeve 11b are slideable on a stationary contact pin 14. The ends of the current circuit to be controlled by the contact device are attached to the stationary contact pin 14 and to the terminal bolt 14a, respectively which is provided on the upper side of the tubular extension 12. The tubular extension 12 and the contact pin 14 are secured to the base plate 15 by insulating supports 7. On this plate a third insulating support 7 is pivotally connected by the axle 16. This support is jointed to the protective sleeve or housing 11b by means of a link 17.

If the insulating support which is rotatable about the axle 16 is pushed downwards, as shown in Fig. 8, the circuit controlled by the contact device is closed. The circuit in the contact device is as follows:—

The stationary contact pin 14, movable contact contact sleeve 10b, protective housing 11b, contact pin 13, contact sleeve 10a, protective housing 11a, tubular extension piece 12, terminal bolt 14a. When the middle insulating support 7 is turned upwards about the axle 16, the current circuit is interrupted between the stationary contact pin 14 and the movable contact sleeve 10b. In interrupting the circuit, the contact pin 13 slides in the tubular extension piece 12 and takes the position as shown in Fig. 9.

The constructional example according to Figures 8 and 9 is particularly suitable for a disconnecting switch for open air plants as securing the contact pieces from moisture and may also be provided with other contact sleeves than those according to Figs. 1-3.

What I claim is:—

1. An electrical contact device comprising a contact pin, a plurality of contact fingers bent at an angle and disposed one after another around the contact pin to form a contact sleeve, each contact finger having a web-like extension at its middle part with a large and a small curved out part, the

smaller curved out part of each contact finger being inserted in the larger curved out part of the next contact finger, the contact fingers being attached to form a contact sleeve.

2. An electrical contact device as claimed in claim 1, in which each contact finger and its web-like extension with curved out parts is formed from a single piece of sheet metal.

3. An electrical contact device comprising a contact pin, a plurality of substantially V-shaped contact fingers each having a web-like extension at its middle part with a large and a small curved out part, the contact fingers being disposed around the contact pin with the smaller curved out part of each contact finger fitting in the larger curved out part of the next contact finger, so as to form a contact sleeve, a cup-like housing pressed from a piece of metal which surrounds the contact sleeve, a securing flange on the side of said housing, and a tongue pressed out of the bottom of said housing forming a second securing flange and leaving an opening adapted for the passage of said contact pin.

4. An electrical contact device comprising a contact pin, a plurality of substantially V-shaped contact fingers each having a web-like extension at its middle part with a large and a small curved out part, the contact fingers being disposed around the contact pin with the smaller curved out part of each contact finger fitting in the larger curved out part of the next contact finger, so as to form a contact sleeve, a protective sleeve surrounding the contact sleeve with openings at each end and guiding plates of rectangular cross section for the contact pin which are adapted to close the ends of said protective sleeve.

5. An electric contact device comprising two contact sleeves each one formed of a plurality of contact fingers bent at an angle and disposed after one another circularly to form said contact sleeves, protective sleeves surrounding said contact sleeves, one of said contact sleeves being arranged stationary and the other contact sleeve being movable, the protective sleeve of said stationary contact sleeve being provided with a tubular extension, a contact pin inserted in said stationary contact sleeve and tubular extension, said contact pin being carried by the protective sleeve of the movable contact sleeve and a second contact pin arranged stationary and cooperating with said movable contact sleeve.

6. An electric contact device comprising two contact sleeves each one formed of a plurality of contact stampings bent at an angle and disposed after one another circularly to form said contact sleeves, each contact stamping having a web-like extension at its middle part with a large and a small

curved out part, the smaller curved out part of each contact stamping being inserted in the larger curved out part of the next contact stamping, protective sleeves surrounding said two contact sleeves, one of said contact sleeves being stationary and carried by an insulating support and the other contact sleeve being movable and carried by a second insulating support being pivoted on a base, 5 the protective sleeve of said stationary contact sleeve being provided with a tubular extension, said pin being carried by the protective sleeve of the movable contact sleeve and a second contact pin cooperating with 10 said movable contact sleeve and arranged stationary on a third insulating support.

7. An electrical contact device comprising a contact pin, a plurality of substantially V-shaped contact fingers each having a web-like extension at its middle part with a large and a small curved out part, the contact fingers being disposed around the contact pin with the smaller curved out part of each contact finger fitting in the larger curved 20 out part of the next contact finger, so as to form a contact sleeve, and tongues bent over laterally on the contact fingers adapted to prevent displacement of the contact fingers in the direction of the longitudinal axis of 25 the contact pin.

8. An electrical contact device comprising a plurality of contact stampings each bent at an angle and each having a large and a small curved out part, the smaller curved 30 out part of each contact stamping being inserted in the larger curved out part of the next contact stamping, and the contact stampings being arranged circularly to form a contact sleeve and a contact pin adapted to 35 be inserted in the centre of the contact sleeve so as to make electrical contact with the contact stampings forming the contact sleeve.

9. An electric contact device comprising a plurality of substantially V-shaped resilient contact fingers, each contact finger having a web-like extension at its middle part, said contact fingers being loosely connected with each other by means of said web-like extension and arranged circularly to form a contact sleeve, and a contact pin adapted to be 40 inserted in the centre of said contact sleeve so as to make electrical contact with the radial inner ends of said contact fingers.

In testimony whereof I have signed my 45 name to this specification.

CESARE CIPPITELLI.
